DESIGN FOR A COMBINED HEARING AID SUPPORT AND SPECTACLES

Robert Alexander Bachmann, New York, N. Y.

Application March 16, 1945, Serial No. 118,526

Term of patent 14 years

(Cl. D57—1)

To all whom it may concern:

Be it known that I, Robert Alexander Bachmann, a citizen of the United States, residing at New York city, in the county of New York and State of New York, have invented a new, original, and ornamental Design for a Combined Hearing Aid Support and Spectacles, of which the following is a specification, reference being had to the accompanying drawing, forming part thereof, in which

Figure 1 is a perspective view of a combined hearing aid support and spectacles embodying my design; and Figure 2 is a front elevation of the combined hearing aid support and spectacles of Figure 1, shown in reverse position with the ends of the bows toward the observer.

I claim:

The ornamental design for a combined hearing aid support and spectacles, as shown.

ROBERT ALEXANDER BACHMANN.
